REEDITING OF TALKING FILMS

John Hays Hammond, Jr., Gloucester, Mass.

Application May 12, 1930, Serial No. 451,663
Renewed January 11, 1934

6 Claims. (Cl. 179—100.3)

The invention relates to acoustic systems and mode particularly to an improved method of re-editing of photographic sound records.

This invention relates more particularly to a system of rerecording photographic film sound records in which the intensity of the second recording is varied at the will of an operator.

The invention provides a method for the re-editing of photographic film sound records in which the quality of the reedited record can be varied at will.

The invention further provides a rerecording system for photographic sound records with independent control of the upper and lower harmonics so as to vary the quality of the rerecorded record.

The invention also provides a method of re-editing of photographic sound records in which the upper harmonics may be increased at the same time that the lower harmonics are decreased and vice versa.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawing forming a part thereof, in which

The single figure illustrates diagrammatically a system of rerecording photographic sound records.

In the following description and in the claims parts will be identified by specific names for convenience, but they are intended to be as generic in their application to similar parts as the art will permit.

Referring more particularly to the form of the invention shown in the accompanying figure, a standard talking moving picture projector 50 is provided with the usual photo-electric cell 51 for receiving the fluctuations of light from the sound record of the film 52. The constant source of light for the sound record is denoted by 51. The cell 51 is connected to the primary of a transformer 53 the secondary of which is connected by two conductors 54 and 55 to two filter circuits 56 and 57. The filter circuit 56, which is a high pass filter, allows high frequency currents to pass, such as those of the upper half of the voice and music range, and the filter 57, which is a low pass filter, allows low frequency currents of the lower half of this range to pass. The filter circuits 56 and 57 are connected to two space discharge tubes 58 and 59, the outputs of which

are connected to the primaries of two transformers 61 and 62.

The secondaries of these transformers 61 and 62 are connected to two potentiometers 63 and 64, the movable contacts of which are moved by means of a handle 65. The potentiometers 63 and 64 are connected to two filter circuits 66 and 67, the condensers of which are variable and are controlled from a handle 68. These condensers are so connected to this handle that, as the capacity of one set is increased, the capacity of the other set is decreased.

The filter circuits 66 and 67 are connected to two space discharge tubes 71 and 72, the output circuits of which are connected to a primary of 15 transformer 73. The secondary of this transformer is connected to a push pull amplifier 74, which includes a transformer 75. This transformer is connected by two conductors 76 and 77 to a loud speaker 78 and through switch 79 and 20 battery 81 to a variable light source 82 which is located in a casing 83 of a recording device. In this casing is mounted a moving picture film 84 which is driven at the same speed as the film in the projector 50 by a shaft 85 which connects the 25 two mechanisms together. In front of the lamp 82 is a lens 86 which focuses the light from the lamp 82 through an aperture 87 upon the sound track of the film 84.

In the operation of the form of the invention shown in the accompanying figure, the moving picture projector 50 is operated in the usual manner, showing the picture on a suitable screen (not shown) and causing the fluctuation of light through the sound track to be received by the 30 photo-electric cell 51. The fluctuating current from this cell then passes through the transformer 53 and to the filter circuits 56 and 57, the former allowing the higher frequencies to pass and the latter the lower frequencies. These 35 currents are then amplified by the space discharge tubes 58 and 59 from which they pass through the transformers 61 and 62 to the potentiometers 63 and 64. Here any desired proportion of the energy may be passed depending upon 40 the setting of the handle 65.

The energy from the potentiometers 63 and 64 then passes through the filters 66 and 67. These are normally in such a position that the frequencies passing through these filters are unaltered and, therefore, the relative intensities of 50 the treble and bass harmonics are the same as those in the original music. If, however, the handle 68 is shifted in one direction, it will increase the capacities in the circuit 66 and decrease 55 the capacities in the circuit 67. This will cause less of the harmonics to be passed in the circuit 66 and more of the harmonics to be passed in the circuit 67. In this way the brilliance of the bass notes is increased and that of the treble notes 60

decreased. If the handle 68 is moved in the opposite direction, the capacities in the circuit 66 will be decreased and those in the circuit 67 increased, thereby making the treble harmonics 5 richer and cutting down on the bass harmonics.

The energy from the circuits 66 and 67 is then 10 amplified by the space discharge tubes 71 and 72 from which it is fed to the push pull amplifier 74 where it is still more amplified and fed to the loud speaker 78 and variable light source 15 82. The light from this source is focused upon the sensitized sound track of the film 84 so that on this track is reproduced the sounds on the original film in the projector 50, but the intensity 20 of these sounds has been increased or decreased by the manipulation of a handle 65 and the relative intensities of the treble and bass harmonics has been changed by manipulating the handle 68.

It is thus seen that a sound record is produced 25 on the film 84 through an editing process which permits the operator to change the total volume and also the relative brilliance of the bass and treble as desired. In this way it is possible to produce a much finer sound record than can be 30 produced by the usual method, as the invention makes it possible to alter the original record and correct for any errors which were made at the time it was recorded.

After the sound record has been made on the 35 film 84, the picture record may be printed upon this film, this record being identical with that of the film 52 in the projector 50. Great care should be exercised in making this record that it be placed in the proper relative position with regard to the sound track. This can readily be 40 accomplished, however, by making suitable markings on the films at the time the record is started. The loud speaker 78 is used so that the operator can hear the results of the changes he is making in the record, and in that way manipulate the 45 handles so as to produce the best effects. It will be understood that, if desired, the sound record on film 52 may be played first with the switch 79 open so the operator can find out how the film sounds before making the final sound record.

Although only one form in which this invention 50 may be embodied has been shown herein, it is to be understood that the invention is not limited to any specific construction but might be embodied in various forms without departing from the spirit of the invention or the scope of the appended claims.

What is claimed is:

1. In a re-editing system, a primary sound record having an imperfect selection recorded thereon, a pick-up device for said sound record, a secondary sound record for recording the selection from said primary sound record in improved condition, a recorder for said secondary sound record, means between said recorder and said pick-up device for dividing the notes for separate treatment into upper and lower ranges with respect to a given dividing point, and devices for treating separately each range simultaneously with the other to vary the relation between the higher and lower pitch notes in that range.

2. In a re-editing system, a primary sound record having an imperfect selection recorded thereon, a pick-up device for said sound record, a secondary sound record for recording the selection

from said primary sound record in improved condition, a recorder for said secondary sound record, means between said recorder and said pick-up device for dividing the sound tones for separate treatment into upper and lower ranges with respect to a given dividing point, devices for treating separately each range to vary the relation between the higher and lower pitch tones in that range, and a common control means for adjusting said last mentioned devices in inverse relation so that the higher notes of one range may be made to predominate in that range at the same time the lower notes of the other range may be made to predominate in that range.

3. In a re-editing system, a primary sound record having an imperfect selection recorded thereon, a pick-up device for said record, a secondary record for recording the selection from said primary record in improved condition, a recorder for said secondary record, a pair of parallel high and low pass paths connecting said pick-up device and said recorder, a fixed high pass filter in one of said paths, a fixed low pass filter in the other of said paths, said high pass filter passing only those notes above a predetermined pitch, said low pass filter passing only those notes below said predetermined pitch, a variable filter connected in said high pass path in series with said high pass fixed filter, a second variable filter in said low pass parallel path in series with said low pass fixed filter and means for operating said variable filters simultaneously in inverse relation to increase the brilliance of the notes in the high pass path while decreasing the brilliance of the notes in the low pass path and vice versa.

4. In a re-editing system, a first sound record having a selection recorded thereon, a pick-up device receiving energy from said record, a recording device fed by said pick-up device, a second sound record fed by said recording device, means between said devices for separating the transmitted energy into upper and lower frequency ranges, a separate filter means for independently controlling the relative transmission of different frequencies in each said ranges and means to simultaneously adjust both of said filter means for varying the tonal characteristics of the transmitted energy.

5. In a sound record system, a pick-up device for picking up a source of sound energy, a translating device fed by said pick-up device, means between said devices for separating said energy into upper and lower frequency ranges, separate filter devices for independently controlling the relative transmission of higher and lower frequencies in each of said ranges and a common control means for simultaneously adjusting said filter devices in inverse relation.

6. In a sound record system, a pick-up device for picking up a source of sound energy, a translating device, a pair of parallel high and low-pass channels between said devices, a fixed high-pass filter in one of said channels, a fixed low-pass filter in the other of said channels, a variable filter in said high-pass channel in series with said fixed high-pass filter, a second variable filter in said low-pass channel in series with said fixed low-pass filter and means for simultaneously operating said variable filters in inverse relation.
